UNITED STATES PATENT OFFICE

2,572,782

REPEATING TOY AIRPLANE PROJECTOR

Larry I. Vaaler and Ingvald J. Hagemo,
La Crosse, Wis.

Application September 27, 1948, Serial No. 51,372

5 Claims. (Cl. 46—81)

1 This invention relates to toys and more particularly to toy airplanes and an ejector therefor.

An object of this invention is to provide an improved ejector of the repeater or magazine type by means of which toy airplanes of the glider type may be ejected with sufficient force to fly a substantial distance.

Another object of this invention is to provide a gun or ejector for toy airplanes having a magazine wherein a plurality of airplanes are positioned, and provided with means whereby one plane may be shifted from the magazine to firing position, from which position the airplane may be ejected by means of a spring-pressed ejector which is held in charged or ready position by means of a spring-pressed trigger.

Another object of this invention is to provide a toy of this kind which can be operated by a small child, but will also provide a source of amusement for adults.

A further object of this invention is to provide a toy airplane for use in a gun of the magazine type, which can be made out of light metal having a rubber tip at the forward end of the fuselage or body so that neither the airplane nor the object struck thereby will be injured.

With the above and other objects in view, our invention consists in the arrangement, combination and details of construction disclosed in the drawings and specification, and then more particularly pointed out in the appended claims.

In the drawings,

Figure 1 is a plan view of a gun and airplane structure embodying this invention,

Figure 2 is a detail side elevation of the device,

Figure 3 is a longitudinal section taken on the line 3—3 of Figure 1,

Figure 4 is a fragmentary sectional view taken on the line 4—4 of Figure 3,

Figure 5 is a sectional view taken on the line 5—5 of Figure 3,

Figure 6 is a fragmentary sectional view taken on the line 6—6 of Figure 2.

Referring to the drawings, the numeral 10 designates generally an elongated tubular barrel which is formed of a pair of transversely arcuate members 11 and 12, each formed at their upper portion with upwardly extending flanges 13 and 14 respectively, defining a channel or slot 15 therebetween.

The barrel members 11 and 12 have extending downwardly therefrom flanges 16 and 17 respectively, and the flange 16 has disposed at its lower edge an elongated transversely arcuate tube forming member 18. The flange 17 has extend-

ing from the lower edge thereof an elongated complementary tube forming member 19. The tube forming member 18 has extending from the lower edge thereof a flange 20 and the tube forming member 19 has extending from the lower edge thereof a flange 21.

The barrel 10 at its inner or rear end has secured thereto a magazine generally designated as 22. The magazine 22 is formed of a bottom wall 23, upright side walls 24, and a substantially U-shaped wall 25 projecting from the side wall 24 and providing a housing for the wings of the toy airplane. The magazine 22 also includes a rear wall 26 and a closure or cover 27 which is hingedly secured to the side walls 24, the cover or closure 27 being formed with downwardly extending wings or sides 28 which are pivotally secured as at 29 to the side walls 24.

The side walls 28 of the cover 27 are adapted to be releasably held with the cover 27 in closed position by means of complementary detents 30 formed on the cover wall 28 and the magazine wall 24.

The cover or closure 27 includes a pair of upwardly offset spaced apart and parallel channel forming members 31 within which the pair of rudders carried by the airplane, to be hereinafter described, are adapted to loosely engage. These offset channel forming members 31 are open at their forward ends so that the rudders of the airplane may readily move out of the members 31.

The cover or closure 27 includes an elongated combined cover and closure 32 which extends over the slot 15 and the cover extension 32 is formed of an upper wall 33 and depending longitudinal flanges 34. The flanges 34 at their rear portions are cut away as indicated at 35, the purpose for which will be hereinafter described.

The flanges 34 at their lower edges are spaced from the upper edges of the flanges 13 and 14, forming a space 36 within which the wings of the airplane are adapted to slidably engage.

The magazine has disposed therein a spring-pressed follower 37 which includes a pair of depending rods 38 which are slidable through bearings or guides 39 carried by the bottom wall 40 of the magazine 22. A spring 41 is disposed about each rod 38, being interposed between the upper side of the bottom wall 23 and the follower 37.

The magazine 22 also has extending downwardly and rearwardly therefrom a hollow handle 42 by means of which the gun may be held in one hand. The magazine 22 is adapted to have positioned therein a plurality of superposed toy

3

airplanes generally designated as 43. Each airplane is formed of an elongated body or fuselage 44 which is formed with a longitudinal slot 45 extending rearwardly from the forward end of the body or fuselage 44 and opening through the rear end of the body.

A resilient or rubber nose 46 is secured to the forward end of the body or fuselage 44 so that the airplane or the object struck thereby will not be injured. The airplane also includes a pair of wings 47 secured across the body 44 adjacent the forward end of the slot 45. The airplane also includes a stabilizer 48 which is secured across the rear end of the slot 45, and the stabilizer 48 has extending upwardly from the opposite ends thereof a pair of rudders or vertical stabilizers 49. These rudders or vertical stabilizers 49 are adapted to engage in the lower sides of the channel members 31, as shown in Figure 4.

In order to provide for the firing or ejecting of an airplane from the gun, we have provided an airplane shifting member 50. This shifting member 50 is constructed in the form of a straight rod 51 which is slidable through a bushing 52 carried by the rear wall 26 of the magazine, and the rod 51 is formed at its inner end with a head or enlargement 53 adapted to abut against the uppermost one of the airplanes disposed in the magazine 22.

An airplane ejector or firing member 54 is disposed forwardly of the magazine 22, being slidably mounted within the barrel 10 and extending downwardly between the flanges 15 and 16 and terminating in a rearwardly extending right angular arm 55 having a trigger engaging lug 56 at its rear or inner end. The ejecting member 54 is adapted to be latched in a firing position by means of a substantially L-shaped trigger 57 pivotally mounted as at 58, between the flanges 20 and 21.

The trigger 57 includes a bill 59 which is engageable with the lug 56. The ejecting member 54 is placed under tension of a spring 60 disposed in the tube formed by the tube forming members 18 and 19 and the spring 60 is tensioned by means of an elongated combined ejector setting or tensioning member and ejector guide 61. The guide 61 is slidable through the bushings 62 and 63 carried by the magazine 22 below the follower 37, and the forward end of the guide member 61 is provided with a head 64 bearing against the forward side of the ejector 54.

At the time the airplanes are loaded into the magazine 22, the follower 37 is initially latched in the innermost and inoperative position by means of a latch 65 pivotally mounted as at 66 on the inner side of one side wall 24 of the magazine 22. The latch 65 engages through a keeper opening 67 formed in the follower 37 and the latch 65 includes a right angularly and outwardly extending extension or arm 68 which extends through an opening 69 formed in the adjacent wall 24 on the magazine.

An operator 70 is formed integral with the arm 68 projecting upwardly and angularly from the side 24 and a spring 71 is interposed between the operator 70 and the adjacent side wall 24. The rear end of the guide member 61 is connected with the airplane shifter or ejector 51 by means of an upwardly and forwardly inclined connecting bar 72. The trigger 57 is under the tension of a spring 73 which is disposed between a pair of guard plates 74 projecting forwardly from the hollow handle 42.

4

In the use and operation of this device, the airplanes 43 are loaded into the magazine 22 by raising the closure 27, and the extension 32. The follower at this time is manually pushed downwardly against the tension of the springs 41 on the rods 32 and latched in its innermost position by the latch member 65. When the desired number of airplanes 43 are placed in the magazine 22, the cover 27 and the extension 32 is swung downwardly to a normal position, with the cover 27 closed and the extension 32 parallel with the flanges 13 and 14 of the barrel 10. The uppermost airplane 43 is adapted to be shifted forwardly to the firing zone or position by pushing the shifter 50 forwardly, thereby moving the uppermost airplane from the magazine to a position where the inclined rear portion 75 of the extension 32 will move the airplane downwardly to a position where the upper end of the ejector 54 will be disposed at the forward end of the slot 45 in the body 44.

The guide rod 61 at this time will be in its foremost position and the ejector 54 may now be released for ejecting of the engaged airplane shown in dotted lines in Figure 3, by pressing the trigger 57. The airplane in the firing zone or position will thereupon be quickly and forcibly moved forwardly with the body 44 loosely passing through the slot 15 formed between the flanges 13 and 14. The ejector 54 is reset by pulling the guide member 61 and ejector or shifter 51 rearwardly until the keeper lug 56 engages the bill 59 of the trigger 57. At this time the head 63 will be disposed at the rear end of the next succeeding airplane 43, which after complete rearward movement of the ejector 51 will be raised to the uppermost position by the spring-pressed follower 37. The airplanes hereinbefore described are adapted to be made out of relatively light material such as aluminum or the like and by providing the magazine hereinbefore described with the ejecting means for ejecting the airplane from the magazine, a number of airplanes may be fired from the gun in fairly rapid succession.

We do not mean to confine ourselves to the exact details of construction herein disclosed but claim all variations falling within the purview of the appended claims.

What we claim is:

1. A toy airplane gun comprising an elongated barrel having a longitudinal slot formed in the top thereof, a magazine at one end of said barrel, a cover hinged to said magazine and formed with a guide extension in spaced relation above said longitudinal slot, a spring-pressed follower in said magazine, a spring-loaded ejector slidably carried by said barrel and disposed forwardly of said magazine, a spring-pressed trigger mounted in the gun and engageable with said ejector for holding the latter in firing position closely adjacent said magazine, a shifter member carried by said ejector having an end disposed in said magazine and longitudinally movable therein for shifting an airplane forwardly from said magazine to the firing position of said ejector whereby the latter upon release from said trigger will discharge said airplane from said barrel.

2. A toy gun and airplane comprising an airplane formed of a lengthwise slotted fuselage, a pair of wings fixed to said fuselage, a tail fixed to the rear of said fuselage, a barrel formed with a lengthwise slot within which said fuselage is adapted to slidably engage, a spring-loaded ejector slidably disposed in said barrel and having a portion thereof projecting into said slot of said

barrel to engage in said slotted portion of the fuselage, a magazine at the rear of said barrel having oppositely extended U-shaped outer side wall portions and adapted to receive a plurality of airplanes in superposed position, a spring-pressed follower in said magazine constantly urging said airplanes upwardly, means for moving the upper one of the airplanes in said magazine forwardly to a firing position engaging said ejector, and a trigger mounted in said gun for releasably holding said ejector in firing position.

3. A toy gun and airplane comprising an airplane formed of a lengthwise slotted fuselage, a pair of wings fixed to said fuselage, a tail fixed to the rear of said fuselage, a barrel formed with a lengthwise slot within which said fuselage is adapted to slidably engage, a spring-loaded ejector slidably disposed in said barrel and having a portion thereof projecting into said slot of said barrel and engageable in said slotted portion of the fuselage, a magazine at the rear of said barrel having side wall extensions and adapted to receive a plurality of airplanes in superposed position, a spring-pressed follower in said magazine constantly urging said airplanes upwardly, means for moving the upper one of the airplanes in said magazine forwardly to a firing position engaging said ejector, said latter named means including combined ejector guide and ejector-loading means, and a trigger mounted in said gun for releasably holding said ejector in firing position.

4. A toy gun for discharging airplanes comprising an elongated barrel having a slot opening upwardly along the upper edge thereof, a magazine at one end of said barrel, a cover hinged to the top of said magazine, an elongated guide member fixed to said cover and extending over said barrel, a spring-pressed follower in said magazine constantly urging the airplanes upwardly, a combined airplane shifter and ejector guide having interconnected parallel members slidably carried by said magazine and barrel respectively, an ejector loosely carried by said ejector-guide and projecting into said slot, a spring about the guide portion of said shifter and ejector guide adapted to constantly urge said ejector forwardly, and means mounted in said gun

for releasably latching said ejector in firing position.

5. A toy airplane gun comprising an elongated barrel, a magazine at one end of said barrel, a cover hinged to said magazine having a channeled guide extension extending forwardly of said magazine to overhang said barrel, a spring-pressed follower in said magazine, means mounted in said gun releasably latching said follower in a retracted position in said magazine, a spring-loaded ejector slidably carried by said barrel and disposed forwardly of said magazine, a firing member carried by said ejector having an end disposed for movement in said barrel, a spring-pressed trigger mounted in said gun and releasably engageable with said ejector for releasably holding the latter in firing position closely adjacent said magazine, and means connected to said ejector and movable therewith with an end portion extending into said magazine for shifting an airplane forwardly from said magazine and along said guide extension to the firing position of said ejector whereby the latter upon release from said trigger will discharge said airplane from said barrel and simultaneously move another airplane from said magazine to a firing position.

LARRY I. VAALER.
